UNITED STATES PATENT OFFICE.

HORACE FALK NEUMAYER, OF MACUNGIE, PENNSYLVANIA.

AUTOMATIC DIE.

1,399,867.

Specification of Letters Patent. Patented Dec. 13, 1921.

Application filed May 29, 1920. Serial No. 385,303.

To all whom it may concern:

Be it known that I, HORACE F. NEUMAYER, a citizen of the United States, residing at Macungie, in the county of Lehigh and State 5 of Pennsylvania, have invented a new and useful Automatic Die, of which the following is a specification.

This invention relates to dies of the automatic or self-opening type.

10 Objects of the invention are to provide a die which has pronounced ease of adjustment, whose blades may be readily removed for replacement or sharpening, which is compact and may be easily swung over the 15 turret base, and whose construction is such that the manufacture thereof is simplified.

A further object is to provide a die of the automatic type which eliminates the use of the unsatisfactory spiral springs ordinarily 20 employed to give the blades a normal tendency to separate.

Other objects will appear as the description is proceeded with.

The invention will be best understood 25 from a consideration of the following detailed description taken in connection with the accompanying drawings forming part of this specification, with the understanding, however, that the invention is not confined 30 to any strict conformity with the showing in the drawings, but may be changed and modified so long as such changes and modifications mark no material departure from the salient features of the invention as expressed in the appended claims.

In the drawings,

Figure 1 is an elevation of a die constructed in accordance with the present invention and adapted to be used with a turret lathe.

Fig. 2 is a top plan view of the same.

Fig. 3 is a section on the line 3—3 of Fig. 2.

Fig. 4 is a longitudinal cross-section on the line 4—4 of Fig. 2.

Fig. 5 is another longitudinal cross-section showing particularly the mounting of the die blades.

Fig. 6 is a transverse cross-section on the line 6—6 of Fig. 5.

Fig. 7 is an elevation looking from the front or left hand end of Fig. 1.

Fig. 8 is a cross-section on the line 8—8 of Fig. 1.

55 Fig. 9 is a section on the line 9—9 of Fig. 4.

Fig. 10 is a detail of the cam ring.

Fig. 11 is a perspective view of one of the die blades.

The die comprises a body proper 12 having an extended shank 16 integral therewith for holding the body in a turret lathe. The body 12 is slotted as indicated at 13 to receive the die blades. In the illustrated embodiment there are four of these slots shown, 60 each to receive a die blade. Obviously, more or less than this number of die blades might be employed. The shank 16 is flattened as indicated at 17 for an obvious purpose.

The body 12 has a raised shoulder 14 adjacent its joining with the shank 16. The slots 13 extend for the entire length of the body 12. Bores 15 are provided on the shoulder 14 intermediate the slots, and pins 19 extend between adjacent bores 15 and provide 75 pivotal elements for the die blades 20. The pins 19 are removable whereby the blades may be taken out for sharpening or for replacement by other blades of different sizes.

A ring 21 is secured to the outer end of 80 body 12 by means of screws or similar elements 22. The ring 21 keeps the slotted body from spreading and also provides an abutment for the blade-adjusting means to be described. The ring 21, as seen most 85 clearly in Fig. 7, will prevent the blades from spreading apart so as to project beyond the periphery of the body 12.

The shank 16 is provided with a number 90 of grooves 18, which grooves are in alignment with the slots 13. The grooves 18 receive flat springs 23 which, as seen in Fig. 5, bear against the under sides of the die blades to impart to the latter a tendency to spread or move outwardly. A collar 24 fits over 95 shank 16 and is provided with set screws 25 passing through the collar and engaging with the ends of the flat springs 23 to maintain the latter in position.

The blades 20 have the usual teeth 26 at 100 their outer ends and ribs 27, the ribs and teeth being provided on opposite edges of the blades. The ribs are designed to be engaged by adjusting means. The adjusting means includes a master ring 28 and a cam ring 44. The master ring is slidably mounted on the body 12 but may not rotate thereon, while the cam ring is rotatably mounted upon the master ring but is incapable of independent longitudinal movement with respect to the body.

110 The master ring 28 fits snugly upon the

body 12 and is prevented from rotating by a stud 29 screwed into the ring and having its lower end extending into a slot 30 provided on the body. There are two slots 30 at diametrically opposite points on the body, as shown in Fig. 4, and these slots, unlike the slots 13, extend for only a portion of the length of the body, stopping short of each end thereof. A T-shaped bar including the leg 31 and head 32 is secured by screws 33 (Fig. 1), to the master ring 28 and is shaped on its under side to fit upon the periphery of body 12. The end of leg 31 remote from the head 32 has a bore 34 for the reception of a set screw which will be described. The width of the bar 31 is greater than the width of the slot 30, whereby the slot will be covered by the bar when the master ring is in that position removed 20 from the outer end of the tool.

A substantially U-shaped bar 35 is secured to the master ring at a point diametrically opposite to where the T-shaped bar 31 is secured. The U-shaped bar 35 is properly shaped to fit over the curved body 12 and has arms 37 fitting against the inner face of the ring 28 and secured thereto by elements 38. The master ring 28 has a slot 36 provided where the U-shaped bar 35 is secured, 30 which slot is in alignment with the passage-way between the arms of the U-shaped member, as shown in Fig. 2. The end of bar 35 remote from its attached end is provided with a bore 39 for the reception of a set screw 40. The bore 34 of the T-shaped bar 31 receives a similar set screw 40. The two set screws 40 are received in the diametrically opposite slots 30, and in conjunction with the stud 29, provide means 40 by which the master ring 28 is prevented from rotary movement with respect to the body proper. Such screws have another function, as will be made clear later.

The master ring 28 is provided with an annular raised shoulder 41 which has notches 42 provided at intervals and extending transversely thereof. Upon the outer side of the ring 28 an annular seat 43 is provided for the cam ring 44.

The cam ring, shown by itself in Fig. 10, has four cam faces 45 which are beveled, each cam face extending for a quadrant. These beveled cam faces are designed to engage with the ribs 27 of the die blades. 55 When the master ring is adjusted in the desired position upon the body with the cam ring in engagement with the ribs of the die blades, it will be clear that by moving the cam ring in either direction, the blades will be forced inwardly or allowed to move outwardly, as the case may be, the springs 23 resisting but not preventing inward movement of the blades. This action may perhaps be best understood by a consideration 60 of Fig. 5. The ribs 27 have their outer

edges appropriately curved as indicated in Fig. 11 to engage with the beveled cam faces 45.

A slide attachment 46 is secured by convenient means, as screws 47, to the cam ring and fits over the shoulder 41 to lock the master ring and cam ring together while permitting rotation of the cam ring. At diametrically opposite points upon the cam ring, a second attachment is provided 75 including a housing 48 having ears 49 secured by screws 50 to the cam ring. This second attachment also embraces the annular shoulder 41 and cooperates with the slide 46 for holding cam ring and master ring 80 together. The housing 48 supports means for engaging with the notches 42, whereby the angular position of the cam ring with respect to the master ring may be maintained. This means includes, as seen in 85 Figs. 4 and 8, a stem 52 carrying a knob 51 at the upper end and a head 55 at the lower end. A spiral spring 53 is contained in the housing 48 surrounding the stem 52 and bearing against the head 55 to impart to the latter a tendency to move to a locked position. The head 55 has a tooth 54 integral therewith adapted to engage with one of the notches 42. The head 55 has a groove 57 therein with which a screw 56 90 engages. The screw 56 prevents rotation of the stem and head within the housing. The knob 51 provides convenient means by which the tooth or pawl 54 may be lifted out of engagement with the notches, whereupon 100 the cam ring may be rotated in either direction, as desired.

The shank 16 has a central longitudinal bore 58 provided to receive an adjusting bar 59 having a head 60 at one end for engagement with the work. The adjusting bar 59 is flattened, as indicated at 61, throughout the greater portion of its length and is shorter than the combined length of the body and shank, as seen in Figs. 4 and 5. The 110 end of the bar adjacent the head 60 is provided with a plurality of screw-threaded bores 62 adapted to receive the screw-threaded end of a set stem 63 which extends upwardly from the adjusting bar through one 115 of the slots 30. The set stem 63 provides means by which the adjusting bar may be moved longitudinally of the die. The upper end of the set stem is received within the slot 36 and between the arms of the U-shaped bar 35. Obviously, when the set stem is moved to the outer or working end of the tool, the head of the adjusting bar will be brought close to the teeth of the die blades. The position of the adjustable bar relative 120 to the body is maintained by the set screws 40 which pass through bores provided in a collar 64 surrounding the adjusting bar 59 and whose inner ends bear against the flattened faces 61. When the set screws 40 are 130

clamped upon the adjusting bar 59, it will be clear that the adjusting bar will be fixed relative to the master ring 28 and the parts carried thereby. When the work is brought 5 into engagement with the head 60, the thrust will be transmitted through the set screws 40 and the bars 31 and 35 to the master ring which will move inwardly, thereby releasing the die blades from engagement with the 10 work; thus the die is an automatic self-opening one. The length of the thread cut by the blades is regulated by the position of the set stem 63 relative to the set screws 40.

When the die blades are parallel, they will 15 cut a thread of standard size. When they are depressed, as by rotation of the cam ring when brought into engagement with the ribs 27, the depth of the cut will be increased. When the die blades are allowed to swing 20 outwardly toward engagement with the outer ring 21, the depth of the cut will be less than standard; thus it is seen that the depth of the threads as well as the length may be varied at will.

25 The tool of the present invention is exceptionally easy and rapid in its adjustment. It is simple in construction and may be readily manufactured. The blades are easily removed for sharpening or replacement by 30 blades designed to cut threads of different sizes. The tool is compact and may be easily swung over the turret base, while other tools of this kind are frequently too large to be so swung. The use of the flat 35 springs is found to offer many advantages over coil springs which it is found continually give trouble. The flat springs may be readily removed by merely loosening the collar 24. In fact, all the parts of the tool 40 are easy to get at. The cam ring, in conjunction with the sliding master ring, provides convenient means by which very exact adjustment of the depth of the thread to be cut may be made.

45 What is claimed is:—

1. In a die, a slotted body, blades pivotally mounted in the slots, flat springs bearing against the under edges of said blades to impart to the latter a tendency to separate, said body having a reduced extension, 50 and a collar mounted on said extension and having clamping screws engaging the springs to hold the ends of each spring against the body.

55 2. In a die, a slotted body, blades pivotally mounted in the slots, grooves in alignment with said slots, flat springs bearing against the under edges of said blades to impart to the latter a tendency to separate, 60 said grooves receiving the ends of said springs and permitting insertion or withdrawal of the same, and means mounted on the body to clamp the springs in position.

65 3. In a die, a slotted body having a reduced extension, blades pivotally mounted

in the slots, grooves in alignment with said slots, flat springs bearing against the under edges of said blades to impart to the latter a tendency to separate, said grooves receiving the ends of said springs and permitting 70 insertion or withdrawal of the same, and a collar mounted on said extension and having clamping screws adapted to hold the ends of each spring in its respective groove.

4. In a die, a hollow body having slots 75 opening into the interior cavity thereof, blades each pivotally mounted in one end in the slots, means forcing the blades apart, and a ring secured to the outer end of the die to prevent the sub-divisions of the body 80 made by the slot from spreading, said ring also acting as a stop for the free ends of the blades.

5. In a die, a slotted body, blades pivotally mounted in the slots, springs bearing 85 against the under edges of said blades to impart to the latter a tendency to separate, a master ring slidable upon said body, and a cam ring rotatably held upon the master ring and engageable with the blades to effect 90 adjustment of the latter.

6. In a die, a slotted body, blades pivotally mounted in the slots, springs bearing against the under edges of said blades to 95 impart to the latter a tendency to separate, a master ring slidable upon said body, and a cam ring rotatably held upon the master ring and engageable with the blades to effect adjustment of the latter, said cam ring having beveled arcuate cam faces, the blades 100 having projecting ribs adapted to be engaged by said cam faces.

7. In a die, a slotted body, blades pivotally mounted in the slots, springs bearing against the under edges of said blades to 105 impart to the latter a tendency to separate, a master ring slidable upon said body, a cam ring rotatably held upon the master ring and engageable with the blades to effect adjustment of the latter, and adjustable means 110 mounted on the cam ring and engageable with the master ring to hold the cam ring in the desired angular relation with respect to the master ring.

8. In a die, a body, blades pivotally 115 mounted on the body, springs imparting to the blades a tendency to separate, means for preventing undue separation of the blades, means for holding the blades in adjusted positions relative to each other, means operable by engagement with the work for releasing the holding means and permitting the blades to spread to their fullest extent, said last-named means comprising an adjusting bar, a set stem secured to the bar, 120 and clamping means for securing the bar and the adjustable blade holding means together.

9. In a die, a body, blades pivotally mounted on the body, springs imparting to 130

the blades a tendency to separate, means for preventing undue separation of the blades, means for holding the blades in adjusted positions relative to each other, means operable by engagement with the work for releasing the holding means and permitting the blades to spread to their fullest extent, said last-named means comprising an adjusting bar, a head at one end of the bar

for engagement with the work, a set stem 10 securable to the bar in a plurality of positions, and clamping means for securing the bar and the adjustable blade holding means together.

In testimony, that I claim the foregoing 15 as my own, I have hereto affixed my signature.

HORACE FALK NEUMEYER.
